(57) CLAIM

The ornamental design for a wall mounted touch screen faceplate, as shown and described.

DESCRIPTION

FIG. 1 is a perspective view of the wall mounted touch screen faceplate;

FIG. 2 is a top view thereof;

FIG. 3 is an orthogonal face view thereof;

FIG. 4 is a bottom view thereof; and,

FIG. 5 is a side view thereof; the opposing side view being a mirror image thereof.
